Patented Dec. 12, 1967

209,546

MULTIPLE ORIFICE SPRAY TIP FOR INSECTICIDES, DISINFECTANTS OR THE LIKE

Fred W. Wahlin, St. Charles, Ill., assignor to Spraying Systems Co., a corporation of Illinois

Filed May 19, 1966, Ser. No. 2,351

Term of patent 14 years

(Cl. D62--2)

FIG. 1.

FIG. 2.

FIG. 3.

FIG. 4.

FIG. 5.

FIG. 6.

FIG. 7.

FIG. 1 is a top view of a spray tip of a multiple orifice spray tip for insecticides, disinfectants or the like type;

FIG. 2 is a rear or back view of the multiple orifice spray tip for insecticides, disinfectants or the like of FIG. 1;

FIG. 3 is a side view of FIG. 1 as seen beneath FIG. 1 as shown;

FIG. 4 is a right side view of FIG. 3;

FIG. 5 is a right side view of FIG. 4;

FIG. 6 is a left side view of FIG. 5; and

FIG. 7 is a prospective view.

I claim:

The ornamental design for a multiple orifice spray tip for insecticides, disinfectants or the like, substantially as shown and described.
